Design No 425.

Charles Muller Design for a Hat-stand

Patented November 18th 1857.

Ms. 425

Charles Miller, of Tompkinsville, N.Y.
Letter Patent No. 425. Dated Nov. 18. 1851.

The schedule referred to in these Letters Patent will make
part of the same.

To all whom it may concern:

Be it known that I, Charles Miller, of the Village of Tompkinsville, Staten Island, County of Richmond, in the State of New York, have invented or produced a new design or figure, to be cast in iron which when thus cast & finished, is termed a hatstand & do hereby declare that the following is a full and exact description of the same.

(The hatstand representing a Triton holding up with both hands a water plant, which also rests upon his head, bending round with a light inclination, the two lower ends, named A & B, in the abjoined drawing; these ends form an umbrella holder, while the corresponding basin C is lying in a bed of leaves & flowers, which form the base & foot of the whole, the Triton resting upon it; the plant above branching out in such manner, as to receive conveniently the hats, for which the structure is intended.

and to be gracefully ornamental at the same time, that I claim as my invention is the design or configuration of a basket or representing a Triton or similar figure, holding up either branches of a plant in the manner aforesaid, with the basin lying in a bed of leaves or flowers, all arranged substantially as aforesaid described and set forth.
